CLAIM

The ornamental design for a socket tool, as shown and described.

DESCRIPTION

FIG. 1 is a front plan view of a socket tool;
FIG. 2 is a top plan view of a socket tool of FIG. 1;
FIG. 3 is a bottom plan view of a socket tool of FIG. 1;
FIG. 4 is a back plan view of a socket tool of FIG. 1;
FIG. 5 is a side plan view of a socket tool of FIG. 1 rotated 90° degrees;
FIG. 6 calls out a sectional view of the front plan view of a socket tool of FIG. 1;
FIG. 7 is an enlarged detail view of the section view on FIG. 6 of a socket tool;
FIG. 8 is a left side and bottom perspective view of a socket tool.
FIG. 9 is a front plan view of an alternate embodiment of a socket tool where the bottom cylindrical portion is shown in a short length;
FIG. 10 is a front plan view of the embodiment of FIGS. 1-8 of a socket tool where the bottom cylindrical portion is shown in a medium length; and,
FIG. 11 is a front plan view of an alternate embodiment of a socket tool where the bottom cylindrical portion is shown in a long length.
